UNITED STATES PATENT OFFICE.

DANIEL S. WAUGH, OF DENVER, COLORADO, ASSIGNOR TO THE DENVER ROCK DRILL & MACHINERY COMPANY, OF DENVER, COLORADO, A CORPORATION OF DELAWARE.

DRILL-BIT-LOCKING MEANS.

1,091,263.

Specification of Letters Patent. Patented Mar. 24, 1914.

Application filed February 20, 1913. Serial No. 749,758.

To all whom it may concern:

Be it known that I, DANIEL S. WAUGH, a citizen of the United States, residing at Denver, in the county of Denver and State of Colorado, have invented new and useful Improvements in Drill-Bit-Locking Means, of which the following is a specification.

The present invention relates more particularly to means for securing the bits in the chucks of rock drills, being especially useful in connection with rock drills of the hammer piston type.

As is well known to those skilled in this art, the drill bits are apt to become lodged in the drill holes, sometimes being so tightly wedged that they cannot be removed except with very considerable force. In any event, the cuttings often get behind the point of the drill and pack sufficiently to hold the bit. In the latter case, if the bit is rotated as it is withdrawn, it can usually be removed without difficulty. During the withdrawing action therefore, it is desirable that the motor be continued in operation in order to effect the said rotation of the bit, but at the same time, it is very undesirable to have the piston hammering upon the bit during this withdrawing action.

One of the important features of the present invention is the provision of means by which the drill bit can be secured to the chuck or motor, and yet has sufficient longitudinal play, so that its inner end is out of the range of the hammering action of the piston. The motor can thus be kept in operation in order to secure the rotary movement of the bit, while said bit is being withdrawn. This means, however, is also so constructed that the bit can be rigidly fixed against play in the chuck and thus to the motor, so that if the bit becomes lodged in the drill hole, sufficient force can be applied to the drilling apparatus to again dislodge it. The means moreover is so constructed that the bit can be entirely free within the chuck, as is the usual case during the drilling operation, to permit the free play of the same and the easy removal of the bit at any time.

The preferred embodiment of the invention is illustrated in the accompanying drawings, wherein:

Figure 1 is a longitudinal sectional view through the drill chuck, equipped with the novel mechanism. Fig. 2 is a sectional view

on the line 2—2 of Fig. 1. Fig. 3 is an end elevation, the bit being shown in cross section.

Similar reference numerals designate corresponding parts in all the figures of the drawings.

The barrel or cylinder member of the motor is designated 4, and located within the same, is a sleeve 5, carrying the usual tappet 6 that is struck by the hammer piston, and in turn, transmits the blow to the drill steel or bit, the inner end portion of which is shown at 7. This bit is received in a bushing 8, the bore 9 of which is angular in cross section to conform to the cross sectional shape of the bit, as will be clear by reference to Figs. 2 and 3. It is secured to the sleeve 5 by a split collar or ring 10, surrounding the end of said sleeve 5, which projects beyond the barrel 4, and is longitudinally slotted, as shown at 11, in order that it may be contracted into clamping engagement with the bushing. The ring or collar 10 is contracted by a transverse bolt 12 that extends across the joint of said ring, and also engages the sleeve 5 and the bushing 8, which is grooved to receive the same. With this combination of parts, it will be evident that when the sleeve 5 is rotated in the barrel 4, the bushing 8 and the drill bit 7 engaged therein, will rotate with it.

The outer projecting end portion of the bushing 8 is provided with an outstanding peripheral flange 13, and is furthermore provided between said flange and the adjacent end of the collar 10 with a transverse opening 14. In this opening, is located a sliding gib 15, the outer end of which is formed with a head 16, the inner end being tapered, as shown at 17, and the ends of said tapered portion being beveled, as illustrated in Fig. 1. This inner end is arranged to engage in a longitudinal groove or socket 18 formed in one side of the drill bit, and terminating short of the rear end thereof. In other words, this groove has end walls forming shoulders.

Rotatably mounted on the projecting end of the bushing 8 and retained in place between the integral flange 13 and the split collar 10, is a holding ring 19 that is thus located over the gib 15. The interior of this ring has a cam portion 20 that is arranged to bear against the head 16 of the gib when the ring is rotated to a predetermined posi-

tion. The ring is furthermore provided with an outstanding actuating head or knob 21, by which it may be readily rotated. When the ring is in the position shown in Fig. 2, the gib 15 may move outwardly, so as to disengage its inner tapered end 17 from the socket or groove 18, in which it may fit. When the ring has moved around a predetermined distance, then the cam face 20 will bear against the outer end of the gib sufficiently to retain the inner end in the said socket, but the engagement will be so loose that the bit will have a limited longitudinal play, for it will be noted by reference to Fig. 1 that the socket or groove 18 is considerably longer than the gib. If it is desired to fix the bit rigidly in the chuck, the ring is moved still farther, in which case, a blow is preferably struck upon the knob or lug 21 by some instrument so as to wedge the parts firmly together. In order to maintain the ring in the first two positions, a spring-pressed plunger 22 is placed in a pocket 23 formed transversely in the ring 19, and the outer end of this plunger is arranged to engage in a central socket 24, or in either of two side sockets 25 formed in the adjacent face of the split ring 10. When the plunger is engaged in the central socket, as illustrated in Figs. 1 and 2, then the gib may be displaced entirely out of the groove 18. When the plunger 22 is in either of the side sockets 25, then the plunger will be maintained in the groove 18, but the bit will still have a limited longitudinal play.

In the ordinary operation of the drill, the ring 19 may either be in the position shown in Figs. 1 and 2, or in a position with the plunger engaged in one of the sockets 25. The blows from the piston will therefore be transmitted through the tappet 6 to the drill bit in the usual manner, and the drill bit will be rotated. If now, it is desired to withdraw the bit from the drill hole and the accumulation of cuttings behind the point of said bit makes it desirable to continue the rotation thereof, during the withdrawing action, then the ring is positioned with the plunger 22 in one of the sockets 25. As the drilling apparatus is moved rearwardly, it will be evident that the inner end of the gib 17 will slide in the groove 18 until it strikes the rear end or shoulder thereof, whereupon the bit will move with the remainder of the apparatus. The rear end of said bit and the tappet will now be in a position so that working blows will not be struck by the hammer, but the piston still being in operation, the bit will continue to be rotated. If, however, the drill bit should become firmly lodged in the hole, so that abnormal force is required to remove it, then the ring is rotated sufficiently to cause the gib to grip the drill bit firmly, and this, as already explained, may be accomplished by striking

the knob 21 with a heavy implement. Extraneous force may now be applied to the drilling apparatus if necessary to dislodge the bit.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. In a rock drill, the combination with a bit-receiving chuck, of a bit that engages therein, and means mounted on the chuck and slidably interlocking with the bit for holding said bit in the chuck against detachment while permitting a limited longitudinal movement of the same in the chuck, said means also being capable of fixed engagement with the bit for securing such bit fixedly against longitudinal movement in the chuck.

2. In a rock drill, the combination with a bit-receiving chuck, of a bit that detachably and slidably engages therein, and common means mounted on the chuck and detachably interlocking with the bit for securing said bit in the chuck while permitting a limited longitudinal play thereof and for securing said bit fixedly against movement in said chuck.

3. In a rock drill, the combination with a bit-receiving chuck, of a bit that slidably and detachably engages therein, common means mounted on the chuck and detachably interlocking with the bit for securing said bit in the chuck while permitting a limited longitudinal play thereof and for securing said bit fixedly against movement in said chuck, and means for maintaining the holding means in the former of its said positions.

4. In a rock drill, the combination with a bit-receiving chuck, of a bit that slidably and detachably engages therein, said bit having an elongated socket, a gib carried by the chuck and movable into and out of the socket, said gib being of less length than the socket, and means for holding the gib loosely and also tightly in the socket, to respectively permit and prevent limited longitudinal play of the bit in the chuck.

5. In a rock drill, the combination with a bit-receiving chuck, of a bit that slidably and detachably engages therein, said bit having an elongated socket, a gib carried by the chuck and movable into and out of the socket, said gib being of less length than the socket, means for holding the gib

loosely and also tightly in the socket to respectively permit and prevent limited longitudinal play of the bit in the chuck, and means for maintaining the holding means 5 in a position to permit the gib to become disengaged from the socket and in a position to maintain such gib loosely in said socket.

6. In a rock drill, the combination with a bit-receiving chuck having a transverse opening therein, of a bit that slidably and detachably engages in the chuck, said bit having an elongated socket with end walls, a gib slidably mounted in the opening and movable into and out of the socket, said gib 10 being of less length than the socket, and a ring rotatably mounted on the chuck and having an internal cam portion that engages the outer end of the gib, said cam portion being movable to a position to permit the gib to move out of the socket, being movable to another position to maintain the gib loosely in the socket to permit a limited longitudinal play of the bit and to a third position in which the gib is maintained 15 tightly in the socket and in engagement with the bit to prevent any longitudinal play of the latter with respect to the chuck.

7. In a rock drill, the combination with a bit-receiving chuck having a transverse opening therein, of a bit that slidably and 20

detachably engages in the chuck, said bit having an elongated socket with end walls, a gib slidably mounted in the opening and movable into and out of the socket, said gib being of less length than the socket a 35 ring rotatably mounted on the chuck and having an internal cam portion that engages the outer end of the gib, said cam portion being movable to a position to permit the gib to move out of the socket, being movable to another position to maintain the gib loosely in the socket to permit a limited longitudinal play of the bit and to a third position in which the gib is maintained 40 tightly in the socket and in engagement with the bit to prevent any longitudinal play of the latter with respect to the chuck, said chuck being provided with spaced sockets, and a spring-pressed plunger carried by the ring and engaging in the sockets to maintain the ring in the first two of said positions.

In testimony whereof I have hereunto set my hand in presence of two subscribing witnesses.

Correction in Letters Patent No. 1,091,263.

It is hereby certified that the assignee in Letters Patent No. 1,091,263, granted March 24, 1914, upon the application of Daniel S. Waugh, of Denver, Colorado, for an improvement in "Drill-Bit-Locking Means," in the heading to the printed specification, was erroneously described and specified as "The Denver Rock Drill & Machinery Company," whereas said assignee should have been described and specified as *The Denver Rock Drill Manufacturing Company*, as shown by the record of assignments in this office; and that the said Letters Patent should be read with this correction therein that the same may conform to the record of the case in the Patent Office.

Signed and sealed this 9th day of June, A. D., 1914.

Acting Commissioner of Patents.

loosely and also tightly in the socket to respectively permit and prevent limited longitudinal play of the bit in the chuck, and means for maintaining the holding means 5 in a position to permit the gib to become disengaged from the socket and in a position to maintain such gib loosely in said socket.

6. In a rock drill, the combination with a bit-receiving chuck having a transverse opening therein, of a bit that slidably and detachably engages in the chuck, said bit having an elongated socket with end walls, a gib slidably mounted in the opening and movable into and out of the socket, said gib 10 being of less length than the socket, and a ring rotatably mounted on the chuck and having an internal cam portion that engages the outer end of the gib, said cam portion being movable to a position to permit the gib to move out of the socket, being movable to another position to maintain the gib loosely in the socket to permit a limited longitudinal play of the bit and to a third position in which the gib is maintained 15 tightly in the socket and in engagement with the bit to prevent any longitudinal play of the latter with respect to the chuck.

7. In a rock drill, the combination with a bit-receiving chuck having a transverse opening therein, of a bit that slidably and 20

detachably engages in the chuck, said bit having an elongated socket with end walls, a gib slidably mounted in the opening and movable into and out of the socket, said gib being of less length than the socket a 35 ring rotatably mounted on the chuck and having an internal cam portion that engages the outer end of the gib, said cam portion being movable to a position to permit the gib to move out of the socket, being 40 movable to another position to maintain the gib loosely in the socket to permit a limited longitudinal play of the bit and to a third position in which the gib is maintained tightly in the socket and in engagement with 45 the bit to prevent any longitudinal play of the latter with respect to the chuck, said chuck being provided with spaced sockets, and a spring-pressed plunger carried by the ring and engaging in the sockets to maintain the ring in the first two of said positions.

In testimony whereof I have hereunto set my hand in presence of two subscribing witnesses.
